TELEVISION APPARATUS

Dénes von Mihály, Berlin-Wilmersdorf, Germany,
assignor to the firm I. M. K. Syndicate Limited,
London, England

Application April 4, 1932, Serial No. 602,972
In Germany April 14, 1931

29 Claims. (CL. 178—6)

My invention relates to television apparatus for splitting up or recombining pictures.

A preferred type of splitting-up or recombining member is a disk having spirally arranged holes. This type is preferred on account of its simplicity and cheapness.

10 Spiral-hole disks as made at present are of sheet metal .1 to .2 millimetres thick and their holes are pitched uniformly along a spiral. When the disk is rotated in the plane of the picture each hole moves along a row of picture spots and the sum of the spots appearing through the holes makes up the complete picture.

There are certain difficulties about the operation of spiral disks in practice. One of them is due to the smallness of their holes. The holes move on arcs of a circle and therefore it is desirable that the curvature of their inner and outer edges should approximately be curved to 15 the same radius as the arcs. This, however, is hardly practicable on account of the smallness of the holes.

Take for instance, the normal size of pictures, 30 by 46 millimetres. Splitting up this picture 20 into 30 lines requires 30 holes at one sq.-millimetre pitched 40 millimetres apart. The perimeter of the disk is 1200 millimetres, and its diameter 380 millimeters. This size is rather inconvenient and so large a disk obviously requires 25 much energy for rotating it. The energy required for synchronization is also considerable and the amplification rate is high.

Therefore it is desirable to reduce the diameter of the disk but this also entails a corresponding 30 reduction in the size of the holes. In a disk of about 200 millimetres diameter the area of the holes would only be .25 sq. millimetres, a size at 35 which the curving of the edges is an impossibility.

40 Conditions become still more unfavorable if the number of picture spots is increased in order to effect a finer splitting-up of the pictures. Splitting up a picture of the standard size into 43 lines with the same area of picture spots 45 would require a disk of 1000 millimetres diameter. With a diameter of 200 millimetres, the area of the holes would be .04 sq. millimetres and such holes could not be made with the degree of exactitude required.

50 It has been attempted to make disks in which the holes were replaced by transparent spots obtained by photographic means but such a disk could be made only of glass or celluloid and could not be thicker than .01 to .02 millimetres, 55 with consideration of light refraction and as-

similation. Glass disks of such thinness are too fragile while celluloid disks are not rigid enough.

Other known means for splitting up and recombining pictures also possess certain poor features. Thus, the mirror wheel requires such a degree of precision and is therefore so expensive, and the energy required for rotation and synchronization is so great that it could not be used for an instrument to be universally adopted. Nor are oscilloscopes satisfactory. The cathode-ray oscilloscope requires very complicated electric auxiliaries and double synchronization and is not suitable for the direct transmission of the images of objects. Conditions are more favorable in the electrodynamic oscilloscope but this 10 instrument has the drawbacks that the splitting-up is effected in a meandering line and that comparatively complicated optical auxiliaries are required.

15 It is an object of my invention to eliminate the 20 drawbacks of the existing splitting-up and recombining means and to provide instrument which is smaller than the existing ones, requires less power for operation and synchronization and effects very fine splitting-up.

To this end, I combine a fixed member for 25 splitting up or recombining the pictures, which may be a drum with holes arranged in a helical, or a flat disk with holes arranged in a spiral line, with a rotary mirror which projects the pictures 30 onto the splitting-up, re-receives them from the recombining member, as the case may be.

The member is held in a fixed position with 35 respect to the rotary mirror but may be adjusted by turning about its axis for correcting phase distortion.

The rotary mirror may be arranged on the shaft of a phonical wheel by which it is rotated.

It is still another object of my invention to 40 increase the light intensity of the picture spots. To this end, I provide a second rotary mirror in combination with a reflector. The second mirror rotates in synchronism with the first mirror. The picture spots from the second mirror are reflected onto a photo-electric cell or, for recombining the pictures, the light of a glow lamp 45 is reflected onto the second mirror by the reflector.

It is still another object of my invention to 50 provide a splitting-up or recombining member which may be adjusted for various numbers of holes or transparent spots, and for various positions of the holes or spots on the perimeter of the barrel.

In the accompanying drawings apparatus em- 55

bodying my invention are illustrated diagrammatically by way of example.

In the drawings

Fig. 1 is a perspective illustration, and

5 Fig. 2 is an axial section, of an apparatus having a drum-shaped splitting-up member,

Fig. 3 is an end elevation of the apparatus, showing a pair of curved photo-electric cells at the sides of the barrel,

10 Fig. 4 is an axial section of an apparatus as shown in Figs. 1 and 2, equipped with a rotary prism for compensating the rotation of the pictures,

Fig. 5 is an axial section of an apparatus having 15 a second rotary mirror with a reflector,

Fig. 6 is a side elevation and

Fig. 7 is an end elevation, viewed from the left in Fig. 6, of an element for a built-up drum.

Fig. 8 is an end elevation of the drum built up 20 from the elements in Figs. 6 and 7,

Fig. 9 shows the two parts of a drum which is built up from a pair of sleeves, and

Fig. 10 is an axial section of an apparatus having a flat disc with holes arranged in a spiral 25 instead of a drum with holes arranged in a helical line.

Fig. 11 shows a detail of the optical part.

Referring now to the drawings, and first to Figs. 1 and 2, 1 is the object to be imaged, 2 is an 30 objective and 3 is a rotary mirror onto which the image of the object 1 is projected. The mirror which may also be a prism or any other reflecting member, is at an angle of 45 degs. to the optical axis of the objective 2 and is rotated about the 35 axis by a motor or any suitable other driving means 4. 6 is a drum-shaped splitting-up or recombining member which is fixed with respect to the rotary mirror 3 and concentric to the optical axis of the objective 2. The drum has a helical 40 row of holes 5.

The image 1' of the object 1 is projected onto the inner wall of the drum 6, moves along the drum wall and is split up by the holes 5. 7 and 8, Fig. 3, are photo-electric cells at the sides of the 45 barrel 6 which are curved to its radius. The cells are illuminated by the picture spots through the holes 5 and the light impulses are translated into current impulses by the cells.

The same apparatus may also be used for re- 50 combining pictures if the photo-electric cells 7, 8 are replaced by glow lamps. The picture spots formed by the holes 5 are successively projected into the objective 2 by the rotary mirror 3 and combined into a picture.

55 The advantages of this apparatus for splitting up or recombining pictures are numerous and important.

First and foremost, it is not necessary to rotate the member 6, the only movable part being the 60 mirror 3, with its low weight and negligible windage. In order to reduce the windage still further the mirror 3 may be arranged in a vacuum chamber (not shown) as already suggested for spiral-hole disks which, however, present considerable 65 difficulties on account of the large diameter of the disks.

The power demand of my apparatus is very low and so is the energy required for synchronization.

The apparatus is quite symmetrical and there 70 is no distortion of the split-up or recombined pictures but the pictures remain perfectly square.

Another important advantage is that due to the fixed arrangement of the drum 6 in determining the size of the drum it is not necessary to consider 75 its easy running so that it may be com-

paratively heavy which favours the exactitude of the holes 5. It will be understood that as weight is no longer a consideration the drum may be built up from comparatively heavy and numerous elements and high exactitude of the holes obtained, as will be described with reference to Figs. 6 to 8.

In apparatus as described with reference to Figs. 1 to 3, the same apparatus may be used for splitting up and recombining pictures without making any change therein, except substituting the photo-electric cell or cells by a glow lamp. If, however, the pictures are split up by an apparatus of other type, and only recombined by my apparatus, means must be provided for compensating the rotation of the picture with the rotary mirror 3. This rotation will occur under all conditions, but is troublesome only if my apparatus is not used for splitting up and recombining. If my apparatus is used for both operations the rotary mirrors at the sender and the receiver compensate each other's rotation.

In other cases, compensation means must be provided, and an example is shown in Fig. 4, which shows a receiver designed as described with reference to Figs. 1 to 3. 9 is a triangular prism arranged intermediate the mirror 3 and the objective 2. The prism 9 rotates at half the speed of the mirror 3, and then has the effect of another mirror rotating in the opposite direction. Any other suitable optical means, such as a mirror, a system of lenses and the like (not shown) may be provided instead of the prism 9. The prism 3 and the prism 9 can be driven by the same phonic wheel having two 35 pole wheels the one of them having half the number of poles of the other one. In this case (not shown) the pole wheels are connected to concentrical hollow shafts and the mirror is arranged within and fixed to the inner shaft while the prism is fixed to the outer shaft which belongs to the pole wheel having the greater number of poles and therefore, is rotating with half the speed of the inner shaft.

In the apparatus described, it is not necessary 45 that the area of the holes 5 should be equal to the area of the picture spots as the picture can be magnified or reduced as desired by the objective 2. Therefore the holes 5 may be as large as one sq. centimetre but their edges should be staggered for the width of the picture spots in the axial direction of the drum 6. The width of the picture spots may be 1 millimetre, for example. This permits a very considerable increase of the light intensity as the intensity increases with 55 the area of the holes, being, for instance, 100 times greater for a hole of one sq. centimetre than for one of one sq. millimetre.

Other means for increasing the intensity will be described with reference to Fig. 5. The apparatus described, with the drum 6, is surrounded by a conical reflector 22. 23 is a similar reflector arranged in line with reflector 22, and 24 is a second mirror which rotates in synchronism with the first mirror 3, being preferably arranged on 60 the same shaft at the opposite side of motor 4. 25 is a condenser in the extension of the optical axis, and 26 is a photo-electric cell.

The light rays passing through holes 5 are reflected onto the reflector 22 by the first mirror 70 3, onto the reflector 23 by the reflector 22, onto the mirror 24 by the reflector 23, and onto the cell 26 by the mirror 24.

The same apparatus may be used for recombinig pictures by replacing the cell 26 by a 75

glow lamp the light of which is concentrated to that hole 5 which is just active. As mentioned, weight is no consideration for the drum 6 and therefore it may be built up from ring-shaped steel elements as will be described with reference to Figs. 6, 7 and 8. 10 is one of the elements which may be of steel. Suppose that the size of the holes 11 in each element 10 is to be .01 sq. millimetre, then the 10 width of each element as well as the width of the hole or slot 11 is .1 millimetre. For a drum having 48 holes at .01 sq. millimetre, 48 elements 10 are pitched at an angle of $7\frac{1}{2}$ degs. for which purpose they are equipped with an indexing projection 12. The several elements are placed in a frame as shown in Fig. 8, with end rings 13 and bolts 14 for holding them assembled. The diameter of this drum, at 4800 picture spots, is only 150 millimetres. Obviously, elements of 20 any thickness may be employed. Thus, with elements .01 millimetre thick, holes of .001 sq. millimetre, with a correspondingly smaller diameter of the drum, will be obtained. The exactitude is by no means reduced by this as punching the 25 slots 11 in the rings is not difficult and the holes are exactly bordered by the edges of the slots and by the sides of the adjacent elements 10. Deflection phenomena are eliminated by gradually widening the slots 11 in the direction of the 30 perimeter of element 10, as shown in Fig. 6. The holes in this manner have practically no wall thickness. Assembling the drum may be facilitated by placing the barrel on a glass templet, and inspecting the position of the holes by 35 means of a source of light in the templet.

Drums built up in the manner described have the advantage that the arrangement of their holes can be altered at any time by adding or removing elements. In order to save the trouble 40 of adjusting the holes as often as an alteration is required, the elements may be made for several pitches. Thus, a drum may have 78 rings or elements, 30 of which are for pictures at 30 lines, and the remaining 48 for pictures at 48 lines. The drum is placed in position by shifting it axially. The drum may also be made so as to be 45 displaced in the direction of its perimeter so that any phase corrections are easily effected.

Another possibility is illustrated in Fig. 9. 50 Here, the drum 15 has a set of slots 16 which extend in parallel to its axis and may be made by etching. 17 is a sleeve which is placed on the drum 15 and has a helical slot 18 which may also be etched. The two slots lay open a row 55 of holes in helical arrangement which are not square but supplement each other.

Referring now to Fig. 10, 20 is a flat disk with spiral holes 21 onto which the light is projected from mirror 3 by means of a tapered reflector 19, as indicated by the arrows. This type of apparatus is also very small, since the disk 20 is fixed and not movable, and so may be made of a very thin glass plate, with the holes 21 made by photographic means.

The holes 5 might also be made photographically, as well as the slots 16 and 18 (Fig. 9).

Fig. 11 shows a particularly advantageous form of the optical part of the apparatus. In order to avoid light losses caused by the distance between the objective 2 and the prism 9, and to enable to give these parts very small dimensions, the prism 9 is arranged rotatably within the objective itself between its two lenses 2' and 2''. These lenses are fixed to a frame 27 which also 75 serves as bearing for the rotor 30 of the phonic

wheel rotating the prism 9 which is arranged in the centre of the rotor. The stator 28 of the phonic wheel is fixed to the frame 27. Another phonic wheel 31 is driving the rotary mirror or prism 29 arranged in the centre of the scanning drum 33 which is encircled by a photocell or glow lamp 32.

I claim:

1. Television apparatus comprising a stationary drum having a plurality of analyzing elements for analyzing or recombining an image thereon in circumferentially spaced relation, and a reflecting means mounted within said drum for rotation about the axis thereof and cooperating with said elements for scanning. 10

2. Television apparatus comprising movable reflecting means for causing a complete image to move along a path and a plurality of stationary analyzing elements in said path spaced longitudinally and transversely thereof. 20

3. Television apparatus comprising a plurality of stationary analyzing elements, and means rotating about an axis to reflect a picture arranged in said axis to said analyzing elements. 25

4. Television apparatus comprising stationary analyzing means, an objective, means rotating about an axis passing through said objective and spaced from said analyzing means to reflect an image formed by said objective upon said analyzing means. 30

5. Television apparatus comprising a plurality of stationary analyzing elements, and means rotating about an axis to reflect a picture arranged in said axis to said analyzing elements, said elements being circumferentially spaced around said 35 axis.

6. Television apparatus, comprising a rotary reflecting means, a plurality of stationary analyzing elements for analyzing or recombining an image circumferentially spaced around the axis 40 of said means, said means cooperating with said elements for scanning, an objective in the axis of rotation of said rotary means, and light deflecting means between said objective and said rotary means to prevent rotation of said image 45 by the rotary means.

7. Television apparatus, comprising a rotary reflecting means, a plurality of stationary analyzing elements for analyzing or recombining an image circumferentially spaced around the axis 50 of said means, said means cooperating with said elements for scanning, an objective in the axis of rotation of said rotary means, and a prism rotatably mounted between said objective and said means. 55

8. Television apparatus, comprising a rotary reflecting means, a plurality of stationary analyzing elements for analyzing or recombining an image circumferentially spaced around the axis 60 of said means, said means cooperating with said elements for scanning, an objective in the axis of rotation of said rotary means, a triangular prism between said objective and said means, and means to rotate said prism at half the speed of rotation of said rotary means. 65

9. Television apparatus comprising a fixed drum having a helical row of apertures for splitting up or recombining the pictures, a rotary reflecting member cooperating with said drum and an objective arranged in the axis of rotation of 70 said rotary member.

10. Television apparatus comprising the combination of a stationary drum provided with helically disposed spaced apertures for analyzing or recombining an image, and a coaxial rotary re- 75

- reflecting member cooperating with said apertures for scanning.
11. Television apparatus comprising the combination of a stationary drum provided with helically disposed spaced apertures for analyzing or recombining an image, coaxial rotary reflecting means cooperating with said apertures for scanning, and electrooptical translating means ex-posed thereto through said apertures.
12. Television apparatus comprising the combination of a fixed drum provided with helically disposed spaced apertures for analyzing an image, coaxial rotary reflecting means cooperating with said apertures for scanning, and light sensitive electric cell means exposed thereto through said apertures.
13. Television apparatus comprising the combination of a fixed drum provided with helically disposed spaced apertures for recombining an image, coaxial rotary reflecting means cooperat-ing with said apertures for scanning, and elec-trically responsive light valve means exposed thereto through said apertures.
14. Television apparatus comprising a fixed drum having a helical row of apertures for splitting up the pictures, a rotary reflecting member cooperating with said drum, an objective ar-ranged in the axis of rotation of said rotary member, and a photo-electric cell arranged out-side said drum and curved to its radius.
15. Television apparatus comprising a fixed drum having a helical row of apertures for re-combining the pictures, a rotary reflecting mem-ber cooperating with said drum, an objective ar-ranged in the axis of rotation of said rotary member and a glow lamp arranged outside said drum and curved to its radius.
16. Television apparatus comprising a fixed disc having spiral rows of apertures for splitting up or recombining the pictures, a rotary reflect-ing member and an objective arranged in the axis of said disc, and a conical reflector adapted to reflect the light rays from said rotary member to said disc.
17. Television apparatus comprising the combination of a stationary disc provided with spi-rally disposed spaced apertures for analyzing or recombining an image, a coaxial rotary reflecting member, and a conical reflector adapted to estab-lish optical paths between said rotary reflector and said apertures successively.
18. Television apparatus comprising, in combi-nation, a fixed drum provided with helically disposed spaced apertures for analyzing or re-combining an image, and, coaxial therewith, a reflector rotatable within said drum, a conical reflector surrounding the drum, a conical reflector opposed to the first, and a second reflector rotatable synchronously with the first, for estab-lishing optical paths through successive apertures between the rotary reflector within said drum and an electrooptical translating device.
19. Television apparatus comprising a fixed drum having a helical row of apertures for splitting up the pictures, a rotary reflecting member, and an objective arranged in the axis of said drum, a conical reflector surrounding said drum, a second rotary reflecting member rotating in synchronism with said first mentioned reflecting
- member, a second conical reflector adapted to reflect the light rays from the first conical reflector to the second rotary member, and a photo-cell adapted to receive the light rays from said second rotary reflecting member.
20. Television apparatus comprising a fixed drum having a helical row of apertures for re-combining the picture, a rotary reflecting mem-ber and an objective in the axis of said drum, a conical reflector surrounding said drum, a glow lamp, a second rotary member rotating in syn-chronism with the first mentioned rotary mem-ber, and a second conical reflector adapted to reflect light rays of the glow lamp from the second rotary member to the first said conical reflector and onto the first mentioned rotary member.
21. Television apparatus according to claim 20 wherein both rotary reflecting members are driven by the same phonic wheel arranged be-tween them.
22. Television apparatus according to claim 1, wherein the apertures of said drum have a larger area than the picture spots and are successively displaced axially of said drum the width of a pic-ture spot.
23. Television apparatus comprising the com-bination of a fixed member having a plurality of spaced means for analyzing or recombining an image, a rotary reflecting member cooperat-ing therewith for scanning, an objective cooperat-ing with said rotary member, a rotary triangular prism interposed between said rotary member and said objective, a phonic wheel for driving said rotary member, and a phonic wheel for driving said prism at half the speed of said rotary mem-ber.
24. Television apparatus according to claim 23 wherein the rotary triangular prism is arranged between the lenses of the objective in the centre of the rotor of a phonic wheel adapted to rotate said prism.
25. Television apparatus according to claim 1 wherein the drum is provided with several helical rows of apertures at different distances, said drum being adapted to be shifted axially so that any of the rows can be brought into cooperation with said rotary reflecting member.
26. Television apparatus according to claim 1, wherein the drum is built up from ring-shaped elements, each element having a slit the width of which is substantially equal to the thickness of the elements.
27. Television apparatus according to claim 1, wherein the drum is built up from ring-shaped elements, each element having a slit the width of which at the inner perimeter of the element being substantially equal to the thickness of the element and increasing from there to the outer perimeter of the element.
28. Television apparatus according to claim 1, wherein the fixed drum consists of two opaque cylindrical parts fitting in one another, one of them being provided with transparent slots ex-tending in parallel to its axis, and the other one being provided with a transparent helical slot.
29. Television apparatus according to claim 1, wherein the drum is adjustable in circumferential direction.

DÉNES VON MIHÁLY.
